UNITED STATES PATENT OFFICE.

JOSEPH PERLSTEIN, OF CHICAGO, ILLINOIS.

DESIGN FOR A COLLAR.

53,046.

Specification for Design.

Patented Mar. 4, 1919.

Application filed June 6, 1918. Serial No. 238,599. Term of patent 7 years.

To all whom it may concern:

Be it known that I, JOSEPH PERLSTEIN, a citizen of the United States, residing at Chicago, in the county of Cook and State of Illinois, have invented a new, original, and ornamental Design for Collars, of which the following is a specification.

The figure is a top view of a collar such as worn by boys and girls, showing my new design.

I claim:

The ornamental design for a collar as shown.

In testimony whereof I affix my signature.

JOSEPH PERLSTEIN.
